UNITED STATES PATENT OFFICE

ALFRED T. CHIDLEY, OF ARLINGTON HEIGHTS, ILLINOIS, ASSIGNOR TO UNION SPECIAL MACHINE COMPANY, OF CHICAGO, ILLINOIS, A CORPORATION OF ILLINOIS

PRESSER FOOT FOR SEWING MACHINES

Application filed June 3, 1929. Serial No. 367,937.

The invention relates to new and useful improvements in a presser foot for sewing machines, and more particularly to a presser foot for guiding the upturned edge portions of fabric sections for trimming and turning down the trimmed portions into flat relation for stitching.

An object of the invention is to provide a presser foot of the above type having a channel for directing the upturned edge portions of fabric sections to the trimming devices, and rigid sections at each side of said channel with non-flexible yielding members attached to said rigid sections so that said members may tilt in either direction and yield bodily whereby fabric sections of varying thicknesses on opposite sides of the channel and also varying thicknesses in the length of the seam may be firmly gripped and held so as to insure a proper trimming and overlapping of the edge portions.

In the drawings:—

Fig. 1 is a top plan view of a presser foot embodying the invention.

Fig. 2 is a bottom plan view of the same.

Fig. 3 is a view of the presser foot from the right hand side in Fig. 1.

Fig. 4 is a sectional view on the line 4—4 of Fig. 1.

Fig. 5 is a sectional view on the line 5—5 of Fig. 1.

Fig. 6 is a sectional view on the line 6—6 of Fig. 1.

The invention is directed to a presser foot for sewing machines for producing a flat seam. Associated with the presser foot are horizontally disposed trimming devices. The presser foot is provided with a channel for directing the upturned edge portions of fabric sections to the trimming devices, and also with means for turning down the trimmed edge portions into flat lapped position for stitching. In the stitching of fabric sections to form a flat seam, sometimes the thickness of the fabric section on one side of the line of stitching is different from that on the other side. Likewise, there is sometimes a variation in the thickness of the fabric in a direction lengthwise of the seam due to cross seams and the like.

The presser foot of the present invention is provided with rigid sections at opposite sides of the channel which direct the upturned edge portions. Mounted on each rigid section is a yielding non-flexible section which may tilt in either direction and which can move bodily so as to accommodate not only the unevenness in the thickness of the two sections at opposite sides of the channel, but also any unevenness in the fabric sections in a direction lengthwise of the seam. Each rigid section is provided with a recess in its under face extending lengthwise thereof and in this recess is mounted the non-flexible member. The non-flexible member is provided with upstanding posts at its opposite ends passing through openings in the rigid section of the foot, which openings are of sufficient size as to permit either end of the foot to be raised or both ends of the foot to be raised at the same time. Springs are provided which surround these posts and which move the non-flexible section downwardly so as to project its under face beneath the face of the rigid section of the presser foot. Stop pins are provided for limiting the extent of movement of the non-flexible member relative to the presser foot.

Referring more in detail to the drawings, the presser foot which embodies the invention includes a shank portion 1 adapted to be attached to the ordinary presser bar. This shank portion has formed integral therewith rigid fabric engaging sections 2 and 3. These rigid sections are spaced so as to form a guiding channel 4 through which the upturned edge portions of the fabric sections are led to the trimming devices.

The trimming devices include a stationary trimming member 5 mounted on the rigid section 3 of the presser foot and a movable trimming member 6 which cooperates with this stationary trimming member. These trimming devices are so disposed relative to the channel 4 that the upturned edge portions of the fabric sections are trimmed, thus preparing the fabric sections for lapping and stitching. Projecting into the channel is an edge turning portion 7. This edge turning portion 7 is fixed to a yielding shank 8 which

is secured to the stationary member 3 by means of a screw 9. This yielding projection forms no part of the present invention except that it is an efficient means for turning down the edge portion of the underlapped fabric section.

Directly in rear of the yielding member and overlying the same is a member 10 carrying the stitch fingers 11 which is also yieldingly mounted and this member 10 insures that the edge portion of the upper lapped fabric section will be turned down so that the two edge portions are lapped one upon the other in flat relation and then directed to the stitching mechanism.

The stitching mechanism may be of any character and the needles operate through the needle opening 12. This member 10 is carried by the rigid section 2 of the presser foot. A screw 13 passes through the shank portion 14 supporting the member 10 and a spring 15 between the head of the screw and the shank portion will yieldingly hold the shank in contact with the upper face of the stationary member 2 of the presser foot.

The rigid section 2 of the presser foot is provided with a recess 16 in its under face. The inner wall of the recess is located close to the wall 17 of the channel 4. This wall 30 of the channel inclines upwardly and inwardly and is shaped in the region opposite the yielding member 7 so as to provide proper clearance for the turning down of the edge portion of the underlapped fabric section. The other wall of the recess 16 is spaced a slight distance from the outer wall of the presser foot. Located in this channel is a non-flexible yielding member 18. This member is provided with an upturned front end portion 18a which is shaped to conform to the upturned edge portion 2a of the rigid section 2. Attached to the member 18 adjacent its front end is a post 19. This post 19 extends through an opening 20 formed in the foot section 2. A spring 21 located in a recess in the foot section 2 bears against a shoulder at the upper end of the recess and against the upper face of the non-flexible member 18. A pin 22 passes through the upper end of the post and is adapted to engage the upper face of the foot section 2 and limit the extent to which the yielding member can be moved from the recess in the under face thereof.

At the other end of the yielding member 18 is a post 23 and a spring 24 with a limiting pin 25 which are similar in construction to those described in connection with the post 19. The yieldingly supported non-flexible member 18 is of sufficient extent that when it is forced into the recess 16 to the limit of its movement, it will become in effect a rigid part of the rigid section 2.

At this time the under face of this member 18 is flush with the under face of the rigid section 2 of the presser foot. The rigid sec-

tion 3 of the presser foot is also provided with a recess 16a in which is yieldingly mounted a non-flexible member 18b. Posts 19a and 23a are attached to this member 18b and springs are provided which are similar to the springs used in connection with the posts 22 and 23 for yieldingly forcing said member 18b downward. A stop pin 22a is associated with the post 19a and a stop pin 25a is associated with the post 23a. This yielding member 18b is located close to the wall 17a of the channel 4 and extends partly across the under face of the foot section 3. It operates in precisely the manner described in connection with the yielding member 18.

These yielding members 18 and 18b are independent of each other. If there are two thicknesses of fabric at one side of the channel and one thickness at the other side thereof, the foot section engaging the two thicknesses will determine the position of the presser foot as a whole. The yielding member bearing on the two thicknesses will be moved into its recess so as to become rigid with its associated foot section. At the other side of the channel, however, the yielding member will move down out of its recess until it contacts with a single thickness of fabric and will properly engage and hold the same.

If there is a cross seam in the fabric of a single thickness, which creates an unevenness in the fabric section along the length of the seam, the yielding section will be moved in order to firmly hold the fabric section in the region adjacent the stitching point. As the cross seam passes underneath the front end of the yielding section the front end only will be raised, while the rear end of the yielding section will remain in contact with the single thickness of the fabric alongside of the stitching point, as this yielding section terminates at the rear of the needle opening, as clearly shown in Fig. 2. As the cross seam continues its rearward movement it will, of course, lift the yielding section bodily as it reaches a point midway between the springs, and as it reaches the rear end of the yielding section, then it alone will be raised tilting the yielding section in the opposite direction so that the forward end thereof engages the fabric section passing beneath the front end of the presser foot.

From the above it will be apparent that a presser foot has been provided with a non-flexible yieldingly supported member at each side of the channel, which guides the upturned edge portions of the fabric sections and these yielding members engage the fabric sections and maintain control of the same regardless of any variation in the thickness of the fabric sections on opposite sides of the channel and also regardless of the variation in the thickness of a fabric section

in the direction of the length of the seam.

Directly at the rear of the presser foot there is a recess 26 in which is mounted a foot section 27 supported by a shank 28 having a slot and screw connection 29 with the shank of the presser foot which permits the section 27 to move upwardly and which limits its downward movement. The springs 30, 30 bear on this section 27 and normally force the same downwardly. This yielding section 27 is provided with a cut away portion 31 in its under face directly in rear of the needle hole. The yielding section serves the purpose of holding the lapped sections firmly in contact with the feeding mechanism and also of engaging the enchainged thread loops for chaining between stitched articles.

It is obvious that minor changes in the details of construction and the arrangement 20 of the parts may be made without departing from the spirit of the invention as set forth in the appended claims.

Having fully described my invention, what I claim as new and desire to secure by Letters 25 Patent, is:—

1. A presser foot for sewing machines comprising a shank, foot portions rigidly carried by said shank, said presser foot having a channel between said foot portions for receiving and directing the upturned edge portions of fabric sections, said presser foot having means for turning said fabric sections into flat overlapping relation for stitching, each foot section having a recess in its under 35 face adjacent the channel, and a non-flexible member rigidly supported in each recess, said non-flexible member being of such extent that when forced into the recess it becomes in effect a rigid part of the section carrying the same.

2. A presser foot for sewing machines comprising a shank, foot portions rigidly carried by said shank, said presser foot having a channel between said foot portions for receiving and directing the upturned edge portions of fabric sections, said presser foot having means for turning said fabric sections into flat overlapping relation for stitching, each foot section having a recess in its under 45 face adjacent the channel, a non-flexible member in each recess, and means for rigidly supporting said members whereby the same may yield independently and move from a rigidly supported position with its under

55 face flush with the under face of the foot section to a rigidly supported position with its under face projecting below the under face of the foot section with which it is associated.

60 3. A presser foot for sewing machines comprising a shank, foot portions rigidly carried by said shank, said presser foot having a channel between said foot portions for receiving and directing the upturned edge portions of fabric sections, said presser foot hav-

ing means for turning said fabric sections into flat overlapping relation for stitching, each foot section having a recess in its under face adjacent the channel, a non-flexible member disposed in each recess, spaced posts rigidly attached to each member and extending through openings formed in the foot section with which it is associated, a spring surrounding each post for rigidly moving the non-flexible member downwardly, and means for limiting the downward movement of said posts.

4. A presser foot for sewing machines comprising a shank, foot portions rigidly carried by said shank, said presser foot having a channel between said foot sections for receiving and directing the upturned edge portions of fabric sections, said presser foot having means for turning said fabric sections into flat overlapping relation for stitching, each foot section having a recess in its under face adjacent the channel, a non-flexible member in each recess, and yielding means at each end of said non-flexible member for moving said member downwardly whereby 85 said member is free to yield at either end thereof and bodily.

5. A presser foot for sewing machines comprising a shank, foot portions rigidly carried by said shank, said presser foot having a channel between said foot sections for receiving and directing the upturned edge portions of fabric sections, said presser foot having means for turning said fabric sections into flat overlapping relation for stitching, each 90 foot section having a recess in its under face adjacent the channel, a non-flexible member in each recess, a supporting and guiding member adjacent the ends of each non-flexible member, springs surrounding said supporting and guiding members and normally pressing said non-flexible member downwardly, and stops to limit the downward movement of said member whereby 95 said non-flexible member is free to yield at either end thereof and bodily.

In testimony whereof, I affix my signature.
ALFRED T. CHIDLEY.
